UNITED STATES PATENT OFFICE.

CARL WALLDOW, OF SAN JOSE, CALIFORNIA.

SACK HOLDER.

Application filed September 19, 1922. Serial No. 589,122.

To all whom it may concern:

Be it known that I, CARL WALLDOW, a citizen of the United States, and resident of San Jose, in the county of Santa Clara and State of California, have invented certain new and useful Improvements in Sack Holders, of which the following is a specification.

It is the object of my invention to provide a device for supporting a sack in an open position for filling.

It is a further object of my invention to provide a device of the character indicated whereby a simple means is provided for holding a sack in the required position prior to positioning the hopper thereover, and whereby the sack may be securely fastened in position for filling by means of elements carried by the hopper itself.

It is a still further object of my invention to provide a device of the character indicated whereby the sack to be filled is securely held in an open position during the filling process, and whereby the raising of the hopper after the sack is filled automatically releases the filled sack.

Finally it is an object of my invention to provide a sacker of the character indicated which is positive in its action, simple in construction, economical to manufacture, and highly efficient in its practical application.

In the drawing:—

Figure 1 is a side elevation of my improved sacker.

Figure 2 is a rear view of a portion of the sacker.

Figure 3 is a cross-section through the sack holding members.

Figure 4 is a side elevation of the sack holding clamp.

Figure 5 is a plan view of the same.

Referring more particularly to the drawing, I show a suitable frame having legs 1 and top and bottom bars 2—3 respectively as shown. The rear legs 1 are extended a distance above the top bars 2 as at 4 and is cut on a bevel as at 5. Pivotaly mounted upon said rear legs by means of hinges 6 is a hopper 7 constructed as shown.

Mounted upon top bars 2 and spaced apart approximately the width of a sack are spring supporting members 8 held in position by screws 9 and having projecting ears 10 formed on the outer side thereof as shown, while passing through ears 10 are pins 11 around which the ends of a spring member 12 are coiled. The member 12 having its

ends 13 projecting downwardly and being in contact with the members 8, the rest of the spring being bent upwardly thence over the upper edge of member 8 and then curved as shown with their inner cross portion 14 curving upwardly to form a portion under which the edge of the sack may be easily slipped. Passing through the upper portion of member 8 and through the bars 2 are orifices 15.

Mounted upon the sides of hopper 7 are sack holding members 16—17, the lower ends of which are pointed and slightly curved as at 18. The location of said members 16—17 upon hopper 7 being such that when the said hopper is in an operative position the pin portions 18 will project into orifices 15 as shown.

The members 16 are placed so as to coincide with the orifices 15 at the front of the sack holder and have a shoulder 19 which engages the upper portion of member 8 and thus supports this edge of the hopper taking the strain off of the hinges 6 as is readily apparent.

The operation of my improved sacker is as follows:—

The hopper being raised as indicated in dotted lines at 20 in Figure 1 the upper edge of the sack to be filled is slipped under the portions 14 of spring members 12, the tension of the springs holding the same in position. The hopper 7 is lowered and the pointed portions 18 of the members 16—17 pass through the sack in entering their respective orifices 15 and thus effectively and positively support the sack without any danger from slipping.

The sack is now securely fastened at four spaced points with the hopper discharging directly into its open mouth. When the sack has been filled through the hopper, the said hopper is raised to the position shown in dotted lines, thereby withdrawing pins 16—17 from engagement with the sack and the orifices 15, the sack now only being held by springs 12. These springs may be held strong enough to support a filled sack until it is withdrawn by the operator, or they may be so constructed as to permit the filled sack to drop to the ground as soon as the hopper is raised. Upon the removal of a filled sack the operation is repeated by again slipping the edge of an empty sack under springs 12 and dropping the hopper into position.

As the weight of the hopper is mainly car-

ried by shoulders 19 on members 16 and the bevelled surfaces 5 of the rear legs 1 the hinges are put under but little strain and will last indefinitely.

5 It may thus be seen that I have provided a new and novel means for holding and releasing a sack placed in my improved device and one which is positive in action, as well as extremely simple in form and construction, economical to manufacture and easily and quickly operated.

It is to be understood, of course, that while I have herein shown and described the preferred embodiment of my invention changes 15 in form, proportion, construction and method of operation may be made within the scope of the appended claims.

I claim:—

1. A sacker comprising a frame, a hopper 20 having downwardly and inwardly inclined sides pivotally mounted thereon, spaced pins arranged on each of two opposite sides of

said hopper to assume a vertical position when the hopper is in an operative position, and means carried by a portion of said pins 25 for engaging said frame to support said hopper thereon.

2. A sacker comprising a frame having orifices formed therein, a hopper pivotally mounted thereon, means for supporting an empty sack in an open position thereon, and means carried by said hopper adapted to pierce said sack and enter said orifices, said last mentioned means having shoulders 30 formed thereon to engage said frame and thereby support said hopper.

3. A sacker comprising a frame having orifices formed therein, a hopper pivotally mounted thereon, resilient clips mounted on said frame to engage sack edges, and means 40 carried by said hopper adapted to pierce said sack at the points grasped by said clips and enter said orifices.

CARL WALLDOW.
